UNITED STATES PATENT OFFICE.

WALLACE WILLIARD PARSONS, OF WASHINGTON, DISTRICT OF COLUMBIA.

MECHANISM FOR LOCKING SPLIT BOLTS.

No. 920,386.

Specification of Letters Patent.

Patented May 4, 1909.

Application filed December 8, 1906. Serial No. 346,942.

To all whom it may concern:

Be it known that I, WALLACE WILLIARD PARSONS, a citizen of the United States, residing at Washington, in the District of Columbia, have invented certain new and useful Improvements in Mechanism for Locking Split Bolts; and I do hereby declare the following to be a full, clear, and exact description of the invention, such as will enable 10 others skilled in the art to which it appertains to make and use the same.

The objects of my invention are: 1. To provide efficient mechanism, connected up to a screw-jack, adapted to engage the ends of a 15 split- or two-membered bolt and to spread said ends in a preferably threadless nut, and to insert a retaining-key between said ends. 2. To provide means, forming part of the aforesaid mechanism, for closing the ends of 20 the bolt on the key to hold the nut. 3. To provide means for adjusting the rear portion of the screw-jack to suit the position of the head of the bolt. 4. To provide means for adjusting, supporting and steadyng the forward part of the screw-jack to suit the requirements of the nut-end of the bolt. 25

With these objects in view, and others appearing as the specification proceeds, the invention comprehends the novel construction, combination, and arrangement of parts of a device characterized by my invention, as will be fully hereinafter set forth in the specification, summed up in the claims, and illustrated in the drawings, in which latter:

35 Figure 1 is an elevation of the screw-jack, together with the mechanism for spreading the ends of the bolt, for inserting a retaining key therebetween, and for closing the ends, and showing, also, in section, a railway-rail 40 and ordinary fish-plates, and a bolt, carrying a collar, passing therethrough; Fig. 2 is a central, vertical, longitudinal section through the mechanism for spreading the ends of the bolt, for inserting a retaining-key therebetween, and for closing the ends of the bolt; 45 Fig. 3 is an end view of the key-inserting block; Fig. 4 is a perspective detail view of the slidble member removed from its carrier-sleeve; Fig. 5 is a detached, detail view 50 of the supporting-legs of my device; Fig. 6 is a fragmentary view of the ends of the bolt, the collar, and the retaining-key; and Fig. 7 is a detail view of the retaining-key.

Referring to the drawings, A indicates a 55 railway-rail, B the ordinary side fish-plates, and C a bolt passing therethrough. This

bolt is desirably two-membered, *i. e.*, has a shank in two separate members, with a solid head *c*, the ends of the bolt being provided with a V-shaped incut *c*². The bolt carries 60 a collar *c*³, which is preferably threadless, and desirably has a cone-shaped opening *c*⁴ therethrough.

A retaining-key *c*⁵ is adapted to be forced through the ends of the bolt and into the 65 collar *c*³ by mechanism hereinafter described, and said key comprises a truncated cone-shaped body or head *c*⁶ and a cone- or wedge-shaped wing *c*⁷ extending from the base of the cone-shaped body-portion *c*⁶. 70

The mechanism for spreading the ends of the bolt, for forcing the retaining-key *c*⁵ therein, and for closing the said ends over the retaining-key comprises the following 75 elements:

A hollow sleeve D is exteriorly threaded, as at *d* and interiorly threaded, as at *d*², and is provided with a head at one end, as at *d*³, and carries a screw-collar *d*⁴ at the opposite end tightly fitting said end. If desired, a 80 set-screw may be used in addition to retain the collar on the sleeve; but this is unnecessary if the collar is made so as tightly to fit the sleeve.

Adapted to be screwed into one end of the 85 sleeve D is a screw-member E, provided with a head *e*.

Adapted to reciprocate in the other end of the sleeve D is the shank *f* of a member F provided with an oblong-shaped solid head 90 *f*² formed with a dished-out, V-shaped end-portion *f*³.

The head *f*² of the member F is adapted to project into a key-inserting block G, through a substantially oblong channel *g* formed 95 therethrough. This block may comprise a substantially circular casting of metal, provided with a circumferential beveled portion *g*² at one end and a V-shaped incut *g*³ also at the end and intersecting the channel *g* at right- 100 angles.

Adapted to support the sleeve D is a hollow interiorly threaded, horizontal arm *h*, of a jack H, and through this arm the threaded sleeve D is screwed. The jack is provided 105 with an arched portion *h*³ terminating in a down-turned arm *h*⁴, provided with a concavity *h*⁵ on its inner surface. The arm *h*⁴ terminates in oppositely-extending feet *h*⁵ adapted to bear upon the lower flanges of the 110 fish-plate B, set-screws *h*⁶ passing through the feet, whereby the leg or arm *h*⁴ may be

raised or lowered to adjust the concavity h^5 so as to bear upon and receive the head c of the bolt C.

Adapted to steady the jack toward the forward portion thereof, or that portion near the arm h , are legs h^7 which are disposed transversely of the arched portion h^3 , and are preferably provided with outwardly extending or flaring feet h^8 . Bolts, or analogous devices, h^9 carrying tightening-nuts pass through the legs h^7 . It will be noted that these supporting means are adjustable, and may be shifted to suit the exigencies of a particular situation.

To position the jack and to assemble the parts of my mechanism, the operation may be described substantially as follows: The jack is positioned so that the arch h^3 extends over the top of the rail A, and the set-screws h^6 screwed down or up until the concavity h^5 is flush with the bolt-head c , which concavity receives and cradles the bolt-head and bears thereagainst. The legs h^7 are also adjusted so that they support the arm h of the jack in the proper position, *i.e.*, so that the opening through the hollow arm h is in the same plane as the bolt C. The sleeve D carrying the screw-member E is then, or previously, screwed through the hollow arm h of the jack, and thereupon the collar d^4 is screwed on the end of the sleeve. The member F is then slipped into the end of the sleeve D, and the key-inserting block G is placed on the head f^2 , the head f^2 telescoping into opening or channel g extending through the key-inserting block. The head c^6 of retaining-key c^5 is then placed in the V-shaped incut g^8 of the key-inserting block G. A strong wrench is then applied to the head d^3 and, being turned, moves the sleeve D forward on the threads of the horizontal arm h , causing the key-inserting block, against which collar d^4 on the sleeve D bears, to bring the key c^5 against the ends of the bolt C; the sharp edge of wing c^7 of the retaining-key c^5 engaging in the V-shaped guiding incut c^2 at the end of the bolt C and forcing the two members of the bolt apart; whereupon continued movement of the sleeve D forces the retaining-key between the two members of the bolt until the wing c^7 of the retaining-key has entered far enough to spread the two members of the bolt against the cone-shaped walls of the opening c^4 of the collar c^3 . The head c^6 of the retaining-key is then entirely within the two members of the bolt.

To lock the retaining-key in place, after having thus been positioned between the two members of the bolt, a strong wrench is applied to the head e of screw-member E, which moves the screw-member forward in the sleeve D, the inner end of the screw-member abutting against the inner end of shank f of member F, causing the same to slide forward, bringing the dished-out, V-

shaped end f^3 of the head f^2 of member F forcibly against the ends of the bolt C, and causing the ends of the two-membered bolt to be closed, or brought together, over the head of the retaining-key.

It will be noted that, during the operation of closing the ends of the bolt over the retaining-key, key-inserting block G remains in its position of forcible pressure against the retaining-key, which key has been forced against the collar c^3 . Thus, there is no possible danger of the collar having any movement whatever laterally on the bolt C. And, when the ends of the bolt C have been closed against or over the retaining-key, the bolt and collar c^3 are firmly locked, and will never work loose. It will also be noted that in my mechanism for inserting the retaining-key c^5 and for closing the ends of the bolt C thereover, I do away with all hammering, which I have found to be injurious in securing a permanent lock of the bolt and collar c^3 ; and that, instead of such violent hammering, causing jar and strain, I apply a gradual pressure to force open the ends of the bolt C, whereby to insert the retaining-key, and also a gradual pressure to cause closing of the ends of the bolt over such retaining-key. Thus I secure a permanent lock, with no danger of the bolt C and collar c^3 working loose in use, and with no weakening of the parts by hammering.

From the above description, taken in connection with the drawings, it will be seen that my mechanism is adapted for use in structural iron work generally, but especially in locking bolts and collars on fish-plates of railway-rails, where its use is eminently advantageous.

Having thus fully described my invention, what I claim as new and desire to secure by Letters-Patent is:

1. In a device for locking two-membered or split-bolts, a hollow sleeve carrying operating means, longitudinally-movable means disposed within and coöperatively engaging with the sleeve and projecting beyond the ends thereof, and a key-inserting member carried by one projecting end of said longitudinally-movable means.

2. In a device for locking two-membered or split-bolts, a hollow sleeve carrying operating means, longitudinally-movable means disposed within and coöperatively engaging with the operating means of the sleeve and projecting beyond the ends of the latter, and a key-inserting member carried by one projecting end of said longitudinally-movable means.

3. In a device for locking two-membered or split-bolts, a hollow sleeve carrying operating means, longitudinally-movable means disposed within and coöperatively engaging with the sleeve and projecting beyond the ends thereof, a key-inserting member carried

by one projecting end of said longitudinally-movable means, and supporting means for the sleeve.

4. In a device for locking two-membered or split-bolts, a hollow sleeve carrying operating means, longitudinally-movable means disposed within and coöperatively engaging with the sleeve and projecting beyond the ends thereof, a key-inserting member carried 10 by one projecting end of said longitudinally-movable means, and supporting means for the sleeve, comprising, in part, a tubular member within which the sleeve is disposed.

5. In a device for locking two-membered or split-bolts, a hollow sleeve carrying operating means, longitudinally - movable means disposed within and coöperatively engaging with the sleeve and projecting beyond the ends thereof, a key-inserting member carried 20 by one projecting end of said longitudinally-movable means, and supporting means for the sleeve, comprising, in part, a tubular member within which the sleeve is disposed and provided with an arched extension.

25 6. In a device for locking two-membered or split-bolts, a hollow sleeve carrying operating means, longitudinally - movable means disposed within and coöperatively engaging with the sleeve and projecting beyond the 30 ends thereof, a key-inserting member carried by one projecting end of said longitudinally-movable means, supporting means for the sleeve, and a supplemental supporting-device carried by the supporting means.

35 7. In a device for locking two-membered or split-bolts, a hollow sleeve carrying operating means, longitudinally - movable means disposed within and coöperatively engaging with the sleeve and projecting beyond the 40 ends thereof, a key-inserting member carried by one projecting end of said longitudinally-movable means, supporting means for the sleeve, formed with an arched extension, and a supplemental depending supporting-device 45 carried by the arch.

8. In a device for locking two-membered or split-bolts, a hollow sleeve carrying operating means, longitudinally - movable means disposed within and coöperatively engaging 50 with the sleeve and projecting beyond the ends thereof, a key-inserting member carried by one projecting end of said longitudinally-movable means, and supporting means for the sleeve; said supporting means comprising a tubular member within which the sleeve is disposed and provided with an arched extension, and depending supporting-legs carried by the arch.

60 9. In a device for locking two-membered or split-bolts, a hollow sleeve carrying operating means, longitudinally - movable means disposed within and coöperatively engaging with the sleeve and projecting beyond the ends thereof, a key-inserting member carried 65 by one projecting end of said longitudinally-

movable means, and supporting means for the sleeve; said supporting means comprising a tubular member within which the sleeve is disposed and provided with an arched extension, and depending legs removably carried by the arch. 70

10. In a device for locking two-membered or split-bolts, a hollow sleeve carrying operating means, longitudinally-movable means disposed within and coöperatively engaging 75 with the sleeve and projecting beyond the ends thereof, a key-inserting member carried by one projecting end of said longitudinally-movable means, and supporting means for the sleeve; said supporting means comprising a tubular member within which the sleeve is disposed and provided with an arched extension, and depending legs adjustably carried by the arch. 80

11. In a device for locking two membered or split bolts, a hollow sleeve carrying operating means, longitudinally-movable means disposed within and coöperatively engaging with the sleeve and projecting beyond the ends thereof, a key-inserting member carried 90 by one projecting end of said longitudinally-movable means, and supporting means for the sleeve; said supporting means comprising a tubular member within which the sleeve is disposed and provided with an 95 arched extension, and depending, removable, adjustable legs carried by the arch.

12. In a device for locking two-membered or split-bolts, a hollow, interiorly-threaded sleeve, a screw-member screwed into the 100 sleeve and projecting beyond one end thereof, a member reciprocating in the sleeve and extending beyond the other end thereof and adapted to be actuated by the screw-member, and a key-inserting member carried by the 105 projecting end of the reciprocating member.

13. In a device for locking two-membered or split-bolts, a hollow, interiorly-threaded sleeve, a screw-member screwed into the sleeve and projecting beyond one end thereof, a member reciprocating in the sleeve and extending beyond the other end thereof and adapted to be actuated by the screw-member, 110 said reciprocating member being provided with a head at its projecting end, and a key- 115 inserting member provided with an opening therethrough engaged by the head of the reciprocating member.

14. In a device for locking two-membered or split-bolts, a hollow, interiorly-threaded 120 sleeve, a screw-member screwed into the sleeve and projecting beyond one end thereof, a member reciprocating in the sleeve and extending beyond the other end thereof and adapted to be actuated by the screw-member, 125 and a key-inserting member carried by the projecting end of the reciprocating member and provided at one end with a V-shaped incut.

15. In a device for locking two-membered 130

or split-bolts, a hollow, interiorly-threaded sleeve, a screw-member screwed into the sleeve and projecting beyond one end thereof, a member reciprocating in the sleeve and extending beyond the other end thereof and adapted to be actuated by the screw-member, said reciprocating member being provided with a head at its projecting end, said head being provided at its end with a V-shaped 10 incut, and a key-inserting member provided with an opening therethrough engaged by the head of the reciprocating member.

16. In a device for locking two-membered or split-bolts, a hollow, interiorly-threaded sleeve, a screw-member screwed into the sleeve and projecting beyond one end thereof, a member reciprocating in the sleeve and extending beyond the other end thereof and adapted to be actuated by the screw-member, 15 said reciprocating member being provided with a head at its projecting end, said head being provided at its end with a V-shaped, dished-out incut, and a key-inserting member provided with an opening therethrough engaged by the head of the reciprocating member.

17. In a device for locking two-membered or split-bolts, a hollow, interiorly-threaded sleeve carrying a collar at one end, a screw-member 20 screwed into the sleeve and projecting beyond one end thereof, a member reciprocating in the sleeve and extending beyond the other end thereof and adapted to be actuated by the screw-member, said reciprocating member being provided with a head at its projecting end, and a key-inserting member provided with an opening therethrough engaged by the head of the reciprocating member.

40 18. In a device for locking two membered or split-bolts, a hollow, interiorly-threaded sleeve carrying a collar at one end, a screw-member 25 screwed into the sleeve and projecting beyond one end thereof, said projecting end being provided with a head, a member reciprocating in the sleeve and extending beyond the other end thereof and adapted to be actuated by the screw-member, said reciprocating member being provided with a head 30 at its projecting end, and a key-inserting member provided with an opening therethrough engaged by the head of the reciprocating member.

19. In a device for locking two-membered or split-bolts, a hollow, interiorly- and exteriorly-threaded sleeve carrying a collar at 35 one end, a screw-member screwed into the sleeve and projecting beyond one end thereof, said projecting end being provided with a head, a member reciprocating in the sleeve and extending beyond the other end thereof and adapted to be actuated by the screw-member, said reciprocating member being provided with a head at its projecting end, 40 and a key-inserting member provided with

an opening therethrough engaged by the head of the reciprocating member.

20. In a device for locking two membered or split-bolts, a hollow, interiorly- and exteriorly - threaded sleeve, a screw - member 70 screwed into the sleeve and projecting beyond one end thereof, a member reciprocating in the sleeve and extending beyond the other end thereof and adapted to be actuated by the screw-member, said reciprocating member being provided with a head at its projecting end, a key-inserting member provided with an opening therethrough engaged by the head of the reciprocating member, and supporting means for the sleeve. 75

21. In a device for locking two-membered or split-bolts, a hollow, interiorly- and exteriorly-threaded sleeve, a screw member 80 screwed into the sleeve and projecting beyond one end thereof, a member reciprocating in the sleeve and extending beyond the other end thereof and adapted to be actuated by the screw-member, said reciprocating member being provided with a head at its projecting end, a key-inserting member provided with an opening therethrough engaged by the head of the reciprocating member, and supporting - means for the sleeve, said supporting means comprising in part a horizontal, hollow, interiorly - threaded arm 85 through which the sleeve is screwed. 90

22. In a device for locking two-membered or split-bolts, a hollow, interiorly- and exteriorly - threaded sleeve, a screw - member 100 screwed into the sleeve and projecting beyond one end thereof, a member reciprocating in the sleeve and extending beyond the other end thereof and adapted to be actuated by the screw-member, said reciprocating member being provided with a head at its 105 projecting end, a key-inserting member provided with an opening therethrough engaged by the head of the reciprocating member, and supporting means for the sleeve, said supporting means comprising, in part, a horizontal, hollow, interiorly - threaded arm 110 through which the sleeve is screwed and a substantially perpendicular arm adapted to bear against the head of the two - membered bolt. 115

23. In a device for locking two-membered or split-bolts, a hollow, interiorly- and exteriorly-threaded sleeve, a screw-member 120 screwed into the sleeve and projecting beyond one end thereof, a member reciprocating in the sleeve and extending beyond the other end thereof and adapted to be actuated by the screw-member, said reciprocating member being provided with a head at its projecting end, a key-inserting member provided with an opening therethrough engaged by the head of the reciprocating member, and supporting means for the sleeve, said supporting means comprising, in part, a horizontal, hollow, interiorly-threaded arm 125 130

through which the sleeve is screwed and a substantially perpendicular arm adapted to bear against the head of the two-membered bolt and provided with a concavity adapted 5 to cradle the bolt-head.

24. In a device for locking two membered or split-bolts, a hollow, interiorly- and exteriorly-threaded sleeve, a screw-member 10 screwed into the sleeve and projecting beyond one end thereof, a member reciprocating in the sleeve and extending beyond the other end thereof, and adapted to be actuated by the screw-member, said reciprocating member being provided with a head at its projecting end, a key-inserting member provided with an opening therethrough engaged by the head of the reciprocating member; and supporting means for the sleeve, comprising, in part, a horizontal, hollow, interiorly-threaded arm through which the sleeve is screwed, and a substantially perpendicular arm adapted to bear against the bolt-head and provided with a concavity adapted to cradle the bolt-head and, at its 25 end, with oppositely-extending feet.

25. In a device for locking two-membered or split-bolts, a hollow, interiorly- and exteriorly-threaded sleeve, a screw-member 30 screwed into the sleeve and projecting beyond one end thereof, a member reciprocating in the sleeve and extending beyond the other end thereof and adapted to be actuated by the screw-member, said reciprocating member being provided with a head at its 35 projecting end, a key-inserting member provided with an opening therethrough engaged by the head of the reciprocating member; and supporting means for the sleeve, comprising, in part, a horizontal, hollow, interiorly-threaded arm through which the sleeve is screwed, a substantially perpendicular arm adapted to bear against the bolt-head and provided with a concavity adapted to cradle the bolt-head and, at its end, with oppositely-extending feet, and set-screws passing 40 through said feet.

26. In a device for locking two-membered or split-bolts, a hollow, interiorly- and exteriorly-threaded sleeve, a screw-member 50 screwed into the sleeve and projecting beyond one end thereof, a member reciprocating in the sleeve and extending beyond the other end thereof and adapted to be actuated by the screw-member, said reciprocating member being provided with a head at its 55 projecting end, a key-inserting member provided with an opening therethrough engaged by the head of the reciprocating member; and supporting means for the sleeve, comprising, in part, a horizontal, hollow, interiorly-threaded arm through which the sleeve is screwed, an arched portion made integral with and merging into one end of said arm, said arched portion terminating, at the other 60 end, in a substantially perpendicular arm

adapted to bear against the bolt-head and provided with a concavity adapted to cradle the bolt-head and, at its end, with oppositely-extending feet, set-screws passing through said feet, and supporting-legs carried by the 70 arched portion and disposed transversely thereof.

27. In a device for locking two-membered or split-bolts, a hollow, interiorly- and exteriorly-threaded sleeve, a screw-member 75 screwed into the sleeve and projecting beyond one end thereof, a member reciprocating in the sleeve and extending beyond the other end thereof and adapted to be actuated by the screw-member, said reciprocating member 80 being provided with a head at its projecting end, a key-inserting member provided with an opening therethrough engaged by the head of the reciprocated member; and supporting means for the sleeve, comprising a horizontal, hollow interiorly-threaded arm through which the sleeve is screwed, an arched portion made integral with one end of said arm, said arched portion terminating, at the other 85 end, in a substantially perpendicular arm 90 adapted to bear against the bolt-head and, at its end, with oppositely-extending feet, set-screws passing through said feet, and adjustable supporting legs carried by the arched portion and disposed transversely thereof. 95

28. A device of the class described, comprising a jaw or body having arms projecting therefrom in parallel planes, a swaging tool supported in one of said arms and provided with an elliptical and converging cavity at 100 one end.

29. A device of the class described, provided with a longitudinally and axially movable member having a detachable swaging tool at one end provided with an elliptical 105 and converging cavity.

30. A device of the class described, comprising a jaw or body having arms projecting therefrom in parallel planes, a swaging-tool supported in one of said arms and provided 110 with an elliptical and converging cavity at one end, and means for applying pressure to the swaging tool.

31. A device of the class described, comprising a jaw or body having arms projecting 115 therefrom, a longitudinally and axially movable swaging-tool supported in one of said arms and having a cavity in one end formed with converging bolt-engaging walls, and wedge-engaging means operable independent 120 of the bolt-engaging walls of the swaging tool.

32. In a mechanism for locking split-bolts, a C-clamp or jaw having a plurality of supporting-arms, a swaging-tool movably 125 supported by one of said arms and having a cavity at one end formed with converging bolt-engaging walls, and means independent of the swaging-tool for engaging a wedge.

33. In a mechanism for locking split- 130

bolts, a C-clamp or jaw having a plurality of supporting-arms, a traveling bolt-engaging member having a cavity in one end formed with converging walls, and wedge-engaging means located outside of the cavity and operable in conjunction with said bolt-engaging member.

34. In a mechanism for locking split-bolts, a C-clamp or jaw having a plurality of supporting-arms, a traveling bolt-engaging member having a cavity in one end formed with converging walls, and wedge-engaging means located outside of the cavity and operable in conjunction with said bolt-engaging member, and means for effecting movement of said bolt-engaging member and wedge-engaging means.

35. A device for locking split-bolts, consisting of a tool-supporting body including an arm or projection, a movable swaging-tool sustained in said arm and provided with a bolt-bending cavity having converging walls, and a wedge-engaging member disposed in coöperative relation to the swaging-tool and movable therewith and operating in advance thereof, substantially as described.

36. A device for locking split-bolts, consisting of a tool-supporting body including an arm or projection, a movable swaging-tool sustained in said arm and provided with a bolt-bending cavity having converging walls, and a wedge-engaging member disposed in coöperative relation to the swaging-tool and movable therewith and, also, independent thereof, substantially as described.

37. A device for locking split-bolts, consisting of a tool-supporting body including an

arm or projection, a movable swaging-tool sustained in said arm and provided with a bolt-bending cavity having converging walls, and a wedge-engaging member disposed in coöperative relation to the swaging-tool and movable therewith and operating in advance thereof, and means for effecting pressure upon said swaging-tool, substantially as described.

38. A device for locking split-bolts, consisting of a tool-supporting body including an arm or projection, a movable swaging-tool sustained in said arm and provided with a bolt-bending cavity having converging walls, and a wedge-engaging member disposed in coöperative relation to the swaging-tool and movable therewith and operating in advance thereof, and means for effecting pressure upon said wedge-engaging member, substantially as described.

39. A device for locking split-bolts, consisting of a tool-supporting body including an arm or projection, a movable swaging-tool sustained in said arm and provided with a bolt-bending cavity having converging walls, and a wedge-engaging member disposed in coöperative relation to the swaging-tool and movable therewith, means for effecting pressure upon said swaging-tool, and independent means for effecting pressure upon said wedge-engaging member, substantially as described.

In testimony whereof, I affix my signature, in the presence of two subscribing witnesses.

WALLACE WILLIARD PARSONS.
